UNITED STATES PATENT OFFICE

IRVING KEMP, OF NEW YORK, N. Y., ASSIGNOR TO CHARLES KEMP, OF NEW YORK, N. Y.

LOCK

Application filed February 9, 1928. Serial No. 252,972.

This invention relates to locks.

In the ordinary construction of door closers provided with spring latches, a knob is generally provided, spaced from the edge of said door. Where it is desired to mount an additional means for locking the door fixedly in position, as, for instance, bolts moving parallel to the vertical edge of the door, it is desirable to have said bolts positioned close to the edge of the door in order to avoid contact with said knob, and also to facilitate the locking action. To carry out this purpose, the present invention provides a locking means wherein a bolt is projected into engagement with a strike, and additional bolt means is positioned to extend along the vertical edge of a door, together with novel actuating means for the last mentioned bolts, operated by the first named bolt.

20 An object of the invention is to provide a simplified locking mechanism, capable of projecting a plurality of bolts in several directions, so assembled that operating means for some of the bolts may be located at any point within a lock casing, within certain limits, in order that such bolts may, if desired, be positioned along an edge of a closure.

Another object of the invention is to provide a novel lock means for projecting and locking bolts, operated by a single key of the ordinary type, without the necessity of using an auxiliary locking mechanism.

A further object of the invention is to provide a lock adapted to project bolts in a plurality of directions, said lock being adapted for mounting in any one of a plurality of positions without change in the mechanism thereof.

40 A still further object of the invention is to provide a lock for projecting lock bolts in opposite directions, said bolts being in substantially the same plane, yet being capable of manufacture without bending, and without the use of loops, etc.

A further object of the invention is to provide a lock for projecting a plurality of bolts in a vertical direction, such lock being provided with counter-balancing means so that

an ordinary key may be used for its actuation.

A still further object of the invention is to provide a locking device for projecting a plurality of bolts, in which a single key both projects and locks these bolts in position.

Other objects of this invention will in part be obvious and in part hereinafter pointed out.

The invention accordingly consists in the features of construction, combinations of elements, and arrangements of parts which will be exemplified in the construction hereinabove described, and of which the scope of application will be indicated in the following claims.

In the accompanying drawing, in which is shown one of the various, possible illustrative embodiments of this invention,

Fig. 1 is a plan view of a lock and the keeper therefor, embodying the invention.

Fig. 2 is a longitudinal sectional view on the line 2—2 of Fig. 1, showing the keeper and lock positioned just before engagement.

Fig. 3 is a transverse sectional view on the line 3—3 of Fig. 2, illustrating the conjunction of the locking bolts and the bolt actuating means.

Fig. 4 is a plan view of the lock casing and its keeper, with the top covering of the casing removed to illustrate the internal assembly thereof.

Fig. 5 is a view similar to Fig. 4, showing a modification of the invention, with parts of the actuating mechanism shown in Figs. 1 to 4 omitted.

Fig. 6 is a sectional view on line 6—6 of Fig. 5, illustrating the bolts and connection means set up therein.

Fig. 7 is a perspective view illustrating the manner in which the lock is set up for use in conjunction with apparatus of the type disclosed in my co-pending application, Serial No. 207,587, filed July 22nd, 1927.

On the drawings, a lock L comprises a lock casing C adapted for co-operation with a strike or keeper K, said casing being formed in any suitable manner, as by casting, so as to provide the body portion 14 and a cover portion 16. Said body portion comprises a

base 10 and an upstanding peripheral wall 12, which may be open at the front end 11 thereof. Body portion 14 may have integrally formed therewith the upstanding lugs 18, 20, adjacent the end 11, said lugs being formed with the semi-circular cut-outs 22. Corresponding lugs 19, 21, are provided to extend from cover 16 and have cut outs 23 provided therein to mate with cut outs 22 and 10 form circular bearing openings. A bolt 24 is receivable through said cut-outs and has one end connected in any suitable manner, or made integral with, a cross head 26, said cross head co-operating in a manner hereinafter 15 described, with a device for imparting reciprocal motion thereto. The free end of bolt 24 is received in opening 28, which may be formed in a lug 30 integral with the base 10 of body portion 14 adjacent end 11 thereof, 20 or in a wall which may extend across said front end of the lock casing C.

A strike or keeper K may likewise be made of a single casting, having a projecting portion 34, formed with an opening 36 transversely extending therethrough. In that construction wherein the lock casing C ends with a wall at end 11 through which a bolt 24 extends, projecting portion 34 will be positioned externally of casing C, so that, when 30 casing C is moved into position adjacent strike K, and bolt 24 is projecting through opening 28 said bolt will enter opening 36 to engage the strike. However, in the preferable construction, as shown on the drawing, base 35 10 of the casing may be formed to receive portion 34 therewithin by having an extension 38 made integral with base 10, said extension being provided with an upstanding wall 40 which connects with the wall 12 of casing C. 40 A slot 44 is formed in extension 38 and is designed to receive portion 34 therethrough, so that said portion will be positioned and retained relative to bolt 24, in such manner that said bolt may properly engage with opening 45 36 to lock the parts together when the bolt is projected.

Carried on bolt 24 and retained between the upstanding lugs 18, 20, is a gear 46 which has a through passage 48 formed transverse the 50 plane of rotation of said gear for receiving said bolt with which it has a substantially smooth sliding fit. A pin 50 extends inwardly from gear 46 into passage 48 and is received in a helical groove 52, cut in the surface of bolt 24. Said gear is adapted to have drive engagement with bars 54, 56, the engaged ends of which are reduced in section, as at 58, said reduced ends having rack teeth 60 cut therein for cooperation with the teeth of gear 46. It will thus be seen that, on reciprocation of bolt 24 into and out of engagement with strike K, pin 50 will be actuated by groove 52 to slide bars 54 and 56 transversely of casing C. The free ends of bars 54 and 56 55 may be formed as bolts to be suitably re-

ceived in properly positioned engagement members, as, for instance, sockets provided in the upper cross-piece and the threshold of a doorway. In order to provide against accidental or unauthorized separation of said 70 rack ends 58 from gear 46, said ends are formed with enlarged portion 62, adapted to engage gear 46 to limit movements of said bars.

Bar 56 may have an offset portion 64 to 75 connect its rack end 58 with the bar so that said bars 54 and 56 may slide in the same plane, and along the same line. By this means, there are provided lock bars sliding in the same line and in the same plane, operable by a very simple mechanism, occupying 80 very little space; so that the lateral and longitudinal dimensions of the lock casing C may be substantially reduced.

If desired, the offset 64 may be within casing C, as shown in the drawings. However, where such offset is housed within casing C, a recess 66 in bar 56 for receiving the rack end 58 of bar 54 must be provided. To properly guide bars 54, 56, in addition to the walls of the upstanding lugs 18, 20, there is provided the projection 68 formed about an opening 69 in wall 12 of casing C. In making up bars 54, 56 it is found desirable, because of the different sizes of doors with which these bars are adapted to cooperate, to make the bars sectional. A portion 70 of the bars 54, 56 is adapted for retention entirely within casing C, or projection 68, at all times. Additional bars 72 may be secured to portion 70 by having countersunk rivets applied, or by a screw connection. In the latter case, a countersunk screw is used and has its head positioned so that it will ride on the side of the lock secured to the closure. A straight rivet connection 105 may be used where the projection 68 is provided; in such construction, said projection protects the joint between portion 70 and bar 72 against unauthorized tampering. However, where the countersunk rivets or screws 110 are used, projection 68 may be eliminated and guides 74, 76 on either side of bars 54, 56 may be cast integral with body portion 14.

As shown on the drawings, cross head 26 is formed with an offset guide 78 having an extending lug 80 received in a longitudinal slot 82 in the base 10 of body portion 14. As additional guide means, a bearing point 84 is formed on guide 78 and rides along the guide surface 86 integrally formed with base 10 so 120 that said cross head is substantially guided for rectilinear motion.

Guide 78 is provided with a pin 88 extending laterally therefrom and having pivotally mounted thereon a locking finger 90. Said finger, at one end, is formed with a double acting catch 92 having the engaging surfaces 94, 96, for purposes hereinafter appearing. The other end of said catch is provided with an inturned arm 93, received in a recess 130

95 formed in guide 78. Said inturned arm has a cam surface 98 adapted to be engaged either by a crank arm 100 secured to the barrel 102 of the key operated by device 104 or by

5 a similar arm 101 actuated either by a finger knob or key actuated means mounted through the side of door opposite barrel 102.

Said key operated device may be of any ordinary type, preferably having the pin-tumbler mechanism commonly in use, and being provided with a face plate 106 received flush on the cover portion therefor. It will be seen that upon insertion of a key (not shown) through opening 109 and then turning said key, barrel 102 and its attached arm 100 will be rotated so that said arm will contact cam surface 98 and rock the locking finger 90 on its pivot pin 88 to release catch 92, as hereinafter appears.

20 A coil spring 110, wound around pin 88 and having engagement with bearing point 84 and a portion of finger 90, will normally tend to return said finger into a position in which catch 92 will engage a part of stop piece 112 to lock movement of guide 78 at a certain point. Stop piece 112 preferably formed integral with base 10 is positioned so that, when cross head 26 is retracted as shown in Fig. 4 and bolt 24 is housed entirely within opening 28 and does not extend outwardly therefrom, surface 94 of catch 92 will have engagement with one edge 114 of piece 112. When cross head 26 has been projected, in a manner hereinafter appearing, so that bolt 24 fully engages opening 28, the other surface 96 of the catch will engage an edge 116 at the other end of slide 112. It will thus be seen that finger 90 with its engaging surfaces positively locks the bolt 24 and its connected devices against reciprocation at the limits of their movement.

To actuate cross head 26 in order to move bolt 24 into engaging position, the arm 101 is rotated so that surface 94 is disengaged from edge 114, finger 90 being moved against the action of spring 110. Continued movement of arm 101 will bring it into contact with cam surface 120 formed as a part of cross head 26 and supply sufficient force to propel cross head 26 and its connected devices, so that bolt 24 and bars 54, 56, will be projected into engagement with their respective parts. Finally, the end 118 of crank arm 101 will slide off surface 120 and release the cam 98 so that finger 90 under action of spring 110, will be moved to bring surface 96 into engagement with edge 116.

In retraction of cross head 26, arm 101 is rotated reversely, and end 118 is brought into contact with surface 98 to depress finger 90 and release catch 92. Continued application of force to arm 101 brings it into engagement with the surface 122 so that cross head 26 will be moved back. Arm 100 will finally

65 ride over surface 122 to clear arm surface 98, catch 92 riding along stop piece 112 in the meantime. Catch 92 will now engage edge 114 and retain the parts in the unlocked position.

70 For the purpose of indicating the positions when the bolt is open and when the bolt is closed, there may be provided a leaf spring 126 retained between the two lugs 128 and 130 so that it normally tends to be deflected downwardly to contact the end 118 of arm 101. A 75 stop 132 restricts said spring against movement downwardly and a stop 134 limits upward movement of said spring. Said spring is provided with an indent 136 into which end 118 co-operates to notify the user that it 80 has arrived at the full position, whether open or closed.

85 Body portion 14 may be provided with any suitable countersunk bolt receiving openings 138 positioned in a line with threaded openings in cover 16, bolts cooperating with these openings to retain the cover 16 on body portion 14, said cover being formed to co-operate with the guides on base 10. Additional openings 144 may be provided through base 12 90 and cover 16 to receive suitable fastening screws to secure the entire lock casing to the support with which the lock is associated. The body of strike or keeper K may likewise be formed with countersunk openings 148 to 95 receive suitable means to fasten said strike to a part to be locked.

100 In the use of the lock illustrated in Fig. 7, there is shown a lock casing C mounted to project the bars 54 and 56, the bar 56 being received through the guide bracket 150 and having pivoted intermediately thereon the two bolts 152, 154, of the type shown and described in my aforesaid co-pending application. The guide 150 is provided with the 105 spring retention means 156 for bolt 154, said means also constituting a fulcrum for bolt 152. Suitable brackets 158 and springs 160 co-operate with the bars 54, 56 to substantially relieve the key actuated bolt in lock casing 110 C of the weight of the bars 54, 56.

115 In the modification shown in Figs. 5 and 6, and assembled as illustrated, wherein the invention is applied to the use of short bolts for conjunction with the ordinary door strike, the rack ends 162, 164, are guided by the up-standing portions 166, 168 formed integral with the casing base. Extending substantially perpendicular to the ends 162, 164 are the connectors 170 from which project the bolt 120 ends 172. These bolt ends are positioned to be received in openings 174 in the strike lugs 176, here shown as projected substantially perpendicular to the plane of lug 178, which is adapted to co-operate with the bolt 24. The 125 base 180 of lock casing 182 is shown as provided with additional openings 184 to receive the lugs 176 therethrough in the same manner as portion 34 is received within opening 44. It will thus be seen that the three bolts will 130

simultaneously co-operate with strike 186, substantially in a manner similar to the operation of the bolts and bars shown in Figs. 1 to 4.

5 It will thus be seen that there is provided a device in which the several objects of this invention are achieved, and which is well adapted to meet the conditions of practical use.

10 As various possible embodiments might be made of the invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by letters patent:—

20 1. In combination, a plurality of relatively movable parts, and means for locking said parts against relative movement, said means including a bolt carried by one part, means for projecting said bolt, a bar, and means pivotally mounted on and actuated by said bolt for positioning said bar.

25 2. In combination, a plurality of relatively movable parts, a plurality of bolts and keepers arranged on said parts, means for actuating one of said bolts into engagement with a keeper, and mechanism pivotally mounted on and controlled by said actuated bolt for projecting the other bolts into engagement with the other keepers.

30 3. In combination, a sliding bolt, a drive device pivotally mounted on said bolt, and co-operating means on said bolt and device for imparting rotary movement to said device, means for projecting said bolt, and a sliding bar actuated by said drive device.

35 4. In combination, a sliding bolt, a drive device, co-operating means on said bolt and device internally of said device for imparting rotary movement to said device, a plurality of bars having means for co-action with said drive device so that operation of said bolt will result in actuation of said bars, and means for projecting said bolt.

40 5. In combination, a sliding bolt, a drive device pivotally mounted on said bolt and co-operating means on said bolt and device for imparting rotary movement to said device, a plurality of bars having means for co-action with said drive device so that operation of said bolt will result in actuation of said bars, and key operated means for moving said bolt.

45 6. In a lock, a plurality of bolts at right angles to each other, a device for actuating one bolt mounted on another of said bolts in relatively movable relation, and cooperating means on said device and on the bolt on which it is mounted for causing relative movement therebetween.

50 7. In a lock, a plurality of bolts at right

angles to each other, a device for actuating one bolt mounted on another of said bolts in relatively movable relation, and cooperating cam means on said device and on the bolt on which it is mounted for causing relative movement therebetween.

In testimony whereof I affix my signature.

IRVING KEMP.
